(57) CLAIM

The ornamental design for a display screen with virtual three-dimensional character icon or display system with virtual three-dimensional character icon as shown and described.

DESCRIPTION

The patent or application file contains a least one drawing/photograph executed in color. Copies of this patent or patent application publication with color drawing(s)/photograph(s) will be provided by the Office upon request and payment of the necessary fee.

FIG. 1 is a front view of a display screen with virtual three-dimensional character icon, or display system with virtual three-dimensional character icon, showing our new design in a front perspective orientation;

FIG. 2 is another front view thereof, showing a rear perspective orientation thereof;

FIG. 3 is another front view thereof, showing a front orientation thereof;

FIG. 4 is another front view thereof, showing a rear orientation thereof;

FIG. 5 is another front view thereof, showing a side orientation thereof;

FIG. 6 is another front view thereof, showing an opposite side orientation thereof;

FIG. 7 is a front view of an alternative embodiment of a display screen with virtual three-dimensional character icon or display system with virtual three-dimensional character icon showing our new design in a front perspective orientation;

FIG. 8 is another front view thereof, showing a rear perspective orientation;

FIG. 9 is another front view thereof, showing our design in a front orientation thereof;

FIG. 10 is another front view thereof, showing a rear orientation thereof;

FIG. 11 is another front view thereof, showing a side orientation thereof; and,

FIG. 12 is another front view thereof, showing an opposite side orientation thereof.

The outermost broken line represents a display screen or a portion of a field of view for a visual display and forms no part of the claimed design.

The virtual three-dimensional character icon in FIGS. 1-6 and 7-12 is shown in various orientations to provide an understanding of the three-dimensional appearance of the design.
